(57) **CLAIM**

The ornamental design for a water purifying filter for refrigerator, as shown and described.

DESCRIPTION

1. Water purifying filter for refrigerator

1.1 is a top and front perspective view.

1.2 is a side elevation view.

1.3 is an opposite side elevation view.

1.4 is a front elevation view.

1.5 is a rear elevation view.

1.6 is a top plan view.

1.7 is a bottom plan view.

1.8 is an alternate perspective view.

The broken line showing of filter head in Reproduction **1.8** is included for the purpose of illustrating environment of the article and forms no part of the claimed design.
